(57) **CLAIM**

The ornamental design for the flexible baseball cover with opening for the sweet spot, as shown and described.

DESCRIPTION

FIG. 1 is a right side view of my new design for a flexible baseball cover with opening for the sweet spot, shown partially stretched over a baseball;

FIG. 2 is a front elevational view of the invention;

FIG. 3 is a rear elevational view of the invention;

FIG. 4 is a left-side elevational view of the invention, the right-side elevational view being a mirror image thereof;

FIG. 5 is a top plan view of the invention; and,

FIG. 6 is a bottom plan view of the invention.

The broken lines showing a baseball in FIGS. 1-6 are included for the purpose of illustrating the invention in use, and form no part of the claimed design.
